UNITED STATES PATENT OFFICE.

GUSTAV H. F. KAYSER, OF WHITAKER, PENNSYLVANIA.

TAP WRENCH.

1,413,660.

Specification of Letters Patent. Patented Apr. 25, 1922.

Application filed May 10, 1920, Serial No. 380,064. Renewed March 11, 1922. Serial No. 543,092.

To all whom it may concern:

Be it known that I, GUSTAV H. F. KAYSER, a citizen of the United States, residing at Whitaker, in the county of Allegheny and State of Pennsylvania, have invented certain new and useful Improvements in Tap Wrenches, of which the following is a specification.

My invention relates to improvements in wrenches and more particularly to a new and improved tap wrench.

Among the objects of the present invention are, to provide a simple and efficient wrench construction capable of being employed as a single handed or a double handed wrench; an adjustable tap wrench including a pair of gripping jaws having simple means for moving one of said jaws relatively to the other; and a tap wrench having a detachable and reversible handle and means cooperating with the handle for securing the handles to the wrench in a plurality of operative positions.

In the accompanying drawings, which illustrate applications of my invention,

Figure 1, is a part side elevational view and a part sectional view of a tap wrench embodying my invention;

Figure 2, a bottom plan view;

30 Figure 3, a vertical sectional view of the wrench structure and an elevational view of the handle showing the latter in a different position than the position of the handle in Figure 1; and

35 Figure 4, a view similar to Figure 1, showing a modified construction.

Referring to the drawings and first to the form of Figure 1, 2 designates a fixed gripping jaw and 3 a movable jaw of a tap wrench. As illustrated and as preferred the jaws are mounted on a horizontally extending bar or member 4, the latter having at one end a screw threaded portion 5 and at or near its other end means for rigidly securing the fixed jaw member 2 thereto. As shown the jaw member 2 is secured to bar 4 by a headed end portion and a pin 6.

Mounted on the threaded end of bar 4 and bearing against the movable jaw 3 is a jaw 40 adjusting member 7. It will of course be understood that in turning the internally threaded member 7 on the threaded portion 5 of bar 4 in one direction, the movable jaw will be moved towards the fixed jaw.

45 8 designates a coiled spring interposed between the jaw-members, the ends of the

spring being disposed in sockets 9 and 10 formed in the respective jaws. The function of this spring is to move jaw 3 away from jaw 2 after the adjusting member 7 has been turned in a direction to open the jaws.

The respective jaws are formed with angular gripping faces or surfaces 11 and 12 and the movable jaw 3 with bevelled faces 13 the latter being provided for the purpose of allowing jaws to be moved very close together.

In addition to the parts mentioned each jaw is formed with a handle receiving opening; the opening 14 of the fixed jaw has its bore slightly tapered while the opening 15 of jaw 3 is straight or non-tapered. The openings 14 and 15 are in line with one another and are adapted to receive a detachable and reversible handle 16.

Handle member 16 preferably comprises a round bar shaped to include a portion *a*, a portion *b*, a tapered portion *c*, connecting the portions *a* and *b*; and an end tapered portion *d*. In the wrench structure shown by Figure 1, the handle projects through the openings of the respective jaw-members and has its tapered portion *c* disposed in contact with the tapered bore of opening 14, thus providing a double handed wrench. The handle may be readily changed from the position shown by Figure 1 to the position shown by Figure 3, in this last mentioned position the structure is what is commonly termed a single handed wrench. In the position the handle assumes in Figure 3 the end tapered portion *d* is entered in the tapered bore of the opening 14.

While I have found that a handle of the character described and employed in conjunction with the tapered opening 14 is a very satisfactory construction, I do not desire to be limited to this particular form of handle and the securing means.

100 In the form of Figure 4, I employ a non-tapered bar or handle 16^a and secure the handle to the fixed jaw in the desired operative positions by means of a set screw 17; in this last described form the opening 14^a 105 is not tapered.

What I claim is:

1. In a tap wrench, a pair of gripping jaws each provided with a handle receiving opening, and a detachable handle entered in said openings, and means whereby the jaws may be adjustably secured on the

handle in a plurality of different longitudinal operating positions.

2. In a tap wrench a pair of gripping jaws, an adjustable detachable handle engaging the jaws, and means for securing the handle to the jaws in a plurality of operative positions relatively to the ends of the handle.

3. In a tap wrench a pair of gripping jaws, an adjustable detachable handle engaging the jaws, and means for securing the handle to the jaws in a plurality of operative positions, said securing means including an opening in one jaw having a tapering bore.

15 4. In a tap wrench, a pair of gripping jaws, an adjustable handle having tapering portions, one of said jaws having a handle receiving opening having a tapering bore adapted to cooperate with the tapered portions of the handle whereby the handle is secured to the jaws in a plurality of operative positions.

5. A tap wrench comprising a detachable and reversible handle, a pair of jaws slidably mounted on the handle, and means whereby the operating position of both of the jaws relatively to the handle may be varied longitudinally of the handle.

30 6. A tap wrench comprising a handle, a pair of jaws on the handle, means whereby the operating position of both of the jaws relatively to the handle may be varied longitudinally of the handle, and means whereby one jaw may be adjusted relatively to the other while the operating position of the jaws remain fixed.

35 7. A tap wrench comprising a handle, a

pair of jaws movable together along the handle to vary the operating position of the jaws relatively to the handle, means for securing the jaws in the positions to which they may be moved, and means for moving one jaw relatively of the other while the operating position remains fixed.

8. A tap wrench comprising a handle, a pair of jaws adjustable relatively to each other, and means whereby the jaws may be moved together along the handle to vary the operating position of the jaws relatively to the handle.

50 9. A tap wrench comprising a detachable and reversible handle, a jaw slidably secured on the handle, a second jaw on the handle movable longitudinally relatively to the first, means for securing the jaws to the handle in a plurality of different operative positions, means for effecting the longitudinal movement of the second jaw, and a compression spring between the jaws tending to hold them apart.

60 10. A tap wrench comprising a handle, a pair of jaws, means whereby the jaws may be secured to the handle at different positions relatively to the ends thereof, means for moving one jaw towards the other when thus secured, and a compression spring between the jaws tending to hold them apart.

In testimony whereof I affix my signature in presence of two witnesses.

GUSTAV H. F. KAYSER.
